UNITED STATES PATENT OFFICE.

ROBERT A. MANWARING AND JAMES T. HESSEL, OF NEW HAVEN, CONNECTICUT.

INSULATOR.

1,140,050.

Specification of Letters Patent. Patented May 18, 1915.

Application filed April 23, 1914. Serial No. 834,011.

To all whom it may concern:

Be it known that we, ROBERT A. MANWARING and JAMES T. HESSEL, citizens of the United States, residing at New Haven, in the county of New Haven and State of Connecticut, have invented a new and useful Improvement in Insulators; and we do hereby declare the following, when taken in connection with the accompanying drawings and the characters of reference marked thereon, to be a full, clear, and exact description of the same, and which said drawings constitute part of this application, and represent, in—

15 Figure 1 a side view of a suspension lamp with a conductor connected with an insulator constructed in accordance with our invention. Fig. 2 a side view of one of our insulators detached. Fig. 3 an underside view of the same. Fig. 4 a view in vertical section of one of the insulators indicating how it is supported and how the twin conductor is attached to it.

This invention relates to an improvement 25 in insulators particularly those attached to a pin and adapted for twin conductors for arc lamps, but applicable for various other places where a conductor is arranged vertically. When a conductor extends in a vertical direction, as for instance, on a pole for an arc lamp, it is desirable that the conductor should be held away from possible contact with the pole or other structure from which the lamp is suspended.

35 The object of this invention is to provide an insulator which may be supported on a bracket with clearance grooves for the conductor; and the invention consists in the construction hereinafter described and particularly recited in the claims.

In carrying out our invention, we form 40 the insulator 2 from porcelain, glass or other insulating material. This insulator has substantially straight sides and the usual threaded central recess 3 whereby it may be attached to the upper end 4 of any suitable bracket or pin 5 and in its lower end it is provided with the usual inner petticoat 6 and outer petticoat 7. At one or more

points, and preferably four, the insulator is 50 formed with vertical grooves or channels 8 extending throughout its length, and around the insulator and intersecting these grooves is an annular groove 9, and preferably and for the purpose of lightening the insulator 55 the space between the vertical grooves 8 will be cut away as at 10, although this is not essential. Our improved insulators are applied in the usual way and as shown in Fig. 1 of the drawings two of them are fixed to 60 a post 11 supporting an arc lamp 12. The twin conductor 13 extends downward substantially parallel with the post and is connected with our insulators 2. The conductors pass through any one of the several vertical grooves 8 as is most convenient, and a plurality of grooves is provided so that when the insulator is screwed onto the supporting bracket one groove will stand in proper position to receive the conductor. 65 These conductors are secured to the insulators by ties 14 which are seated in the annular grooves 9. We thus provide an insulator adapted to have vertically arranged conductors secured to them without bending 70 the conductors and enabling the conductors to be firmly connected with the insulators, and an insulator which is provided with the same insulating properties as insulators adapted to be used for horizontal leads. 75 80

We claim:—

1. A single piece insulator having substantially straight sides, a central pin recess entering the lower end, and formed in its outer surface with a conductor groove extending throughout its length in a plane substantially parallel with the axis of the central recess. 85

2. A single piece insulator having substantially straight sides, a central pin recess 90 entering the lower end, and formed in its outer surface with a plurality of conductor grooves extending throughout its length in a plane substantially parallel with the axis of the central recess. 95

3. A single piece insulator having substantially straight sides, a central pin recess entering the lower end and formed in its

outer surface with a plurality of vertically arranged conductor grooves extending throughout its length in a plane substantially parallel with the axis of the central 5 recess, and with an annular groove arranged at right angles to the conductor grooves and intersecting the same.

In testimony whereof, we have signed this

specification in the presence of two subscribing witnesses.

ROBERT A. MANWARING.
JAMES T. HESSEL.
